FIG. 1 is a perspective view of a first embodiment of the basket showing our new design;

FIG. 2 is a top plan view thereof;

FIG. 3 is a front elevational view thereof;

FIG. 4 is a bottom elevational view thereof;

FIG. 5 is a perspective view of a second embodiment of the basket showing our new design;

FIG. 6 is a top plan view thereof;

FIG. 7 is a front elevational view thereof;

FIG. 8 is a right side elevational view thereof;

FIG. 9 is a bottom plan view thereof;

FIG. 10 is a perspective view of a third embodiment of the basket showing our design;

FIG. 11 is a top plan view thereof;

FIG. 12 is a front elevational view thereof;

FIG. 13 is a right side elevational view thereof; and,

FIG. 14 is a bottom plan view thereof.

The dotted-line showing in the drawings illustrates environmental matter and forms no part of the claimed design.
